UNITED STATES PATENT OFFICE.

JOHN L. MCKAY, OF MINNEAPOLIS, MINNESOTA, ASSIGNOR OF ONE-HALF TO ROBERT L. FORREST, OF MINNEAPOLIS, MINNESOTA.

EXTENSION-TABLE.

1,206,123.

Specification of Letters Patent.

Patented Nov. 28, 1916.

Application filed November 4, 1915. Serial No. 59,593.

To all whom it may concern:

Be it known that I, JOHN L. MCKAY, a citizen of the United States, residing at Minneapolis, in the county of Hennepin and 5 State of Minnesota, have invented certain new and useful Improvements in Extension-Tables, of which the following is a specification.

My invention relates to extension tables 10 and has for its object to provide leaves for such tables having means for connecting the leaves in the table with their upper surfaces in the planes of the polished end portions, as is usual, and also means for connecting 15 the leaves in the table with the surfaces of the leaves projected above that of the table a determined distance so that protective pads may be applied to the polished end portions and the surfaces of said pads will then coincide with the surfaces of the leaves. This 20 makes it practicable to employ protective pads for the polished end sections of the table and to use such pads not only when the table is closed, but also when it is extended, without incurring the additional expense of securing pads to correspond to all 25 of the leaves of the table. In accomplishing these objects I provide the end sections and adjacent leaves with dowel pins in two sets 30 of holes in the leaves, thus permitting of insertion at two heights. I further provide blocks under all of the leaves for raising said leaves above the level of the table, which blocks may be withdrawn or swung aside 35 to allow the leaves to assemble in the ordinary manner.

The full objects and advantages of my invention will appear in connection with the detailed description thereof and are particularly pointed out in the claims.

In the drawings, illustrating the application of my invention in one form,—Figure 1 is a bottom view of an extension table with my improvements employing one leaf, showing 45 the arrangement of the dowels, holes and blocks when said leaf is elevated above the rest of the table. Fig. 2 is a view similar to Fig. 1 where two leaves are employed. Fig. 3 is a view similar to Fig. 1 where three 50 leaves are employed. Figs. 4, 5 and 6 are cross sectional views taken along the dowels of the table shown in Figs. 1, 2 and 3, respectively. Fig. 7 is a view similar to Fig. 6 showing the leaves assembled in the usual 55 manner, presenting a flush top. Fig. 8 is a

side view of a portion of one of the edges of a leaf showing the arrangement of the holes for receiving the dowels. Fig. 9 is a view of a portion of a leaf showing a modified form of elevating block. Fig. 10 is a view 60 similar to Fig. 9 of a device for procuring two heights of elevation.

For the purpose of my invention an ordinary extension table is used in which the leaves are slightly modified. In Figs. 1, 2 65 and 3 is shown a circular-top table 10 comprising the halves 11 and 12 adapted to extend and close up on runners 13 and 14. The top portions 11 and 12 are provided as usual with dowel pins 15 and 16 which engage corresponding holes 17 and 18 in the respective top portions to close the table when no leaves are used. These dowels may be arranged as shown, part on portion 11 and part on portion 12, or they may be entirely placed upon 70 one of these portions.

Table pads are made in two halves 26 and 27 to fit a table when the same is closed, and these halves are usually hinged together but may be procured separate to be used with 75 my invention.

In applying my invention three forms of leaves are used, one form being applied when one leaf is used, a second form being added when two leaves are used, and a third 85 form being added when three or more leaves are used. This will become evident from the drawings and the following description.

In Fig. 1 is shown a table partly extended with a leaf 19 in place and ready to be 90 closed up. Leaf 19, as is customary, is provided with holes 20 and 21 which are arranged to engage the dowel pins 15 and 16 when the table is used in the ordinary manner. In addition to the holes 20 and 21 are 95 provided a second set of holes 22 and 23, as seen in Fig. 8, immediately below said last-named holes and drilled in blocks 24 and 25 glued to the underside of said leaf. With this arrangement dowel pins 15 and 16 can 100 be inserted in holes 20 and 21 or holes 22 and 23, as desired, to make the table top flush or to give the leaf 19 a superelevation over the remaining portion of the table, so that the portions 26 and 27 of the pad may 105 be placed upon the corresponding end portions of the table, giving these portions protection against heat and moisture without incurring the additional expense of purchasing similar pads for the leaves and yet 110

providing a flush surface to the whole table. Fig. 4 shows the pins 15 and 16 inserted in the lower holes 22 and 23 with pads 26 and 27 in place.

5 To remove most of the weight off from the dowel pins each leaf is provided with a pair of blocks 28 and 29 screwed to the respective leaves at 30 and 31 in such a manner that said blocks may be swung under 10 the runners 13 and 14, or to the side as shown in dotted lines in Fig. 1, to correspond to the position of the leaves relative to said runners.

15 In using two leaves the leaf 19 is still maintained and an additional leaf 32 is employed. This leaf is quite similar to leaf 19 and is provided with two sets of holes 33 and 34 in one edge, and with dowel pins 35 in the other edge. The dowel pins 16 in the 20 table portion 11 may engage either holes 33 or holes 34, depending upon whether it is desired to have the top flush or to have the leaves elevated. Dowels 35 in leaf 32 always engage the holes 21 in leaf 19, and dowels 25 15 in table portion 12 may, similarly to dowels 16, engage either of the holes 20 or 22 to secure the flush or elevated relation of the leaves and the top. Leaf 32 is also provided with blocks 29 which permit of 30 the leaf being in an elevated or normal position similar to leaf 19. The relation of the parts in the elevated position is shown in Figs. 2 and 5.

35 When three or more leaves are used, as shown in Figs. 3 and 6, the additional leaves are all of the ordinary form, having at one side one set of holes 37 in which dowel pins 35 of the leaf 32 may be inserted, and at the other side pins 38 insertible in the holes 40 21 of leaf 19. Leaves 36 are, however, provided with blocks 29, which serve the same purpose as on the other leaves. Several of leaves 36 may be joined together and still be inserted between leaves 19 and 32. As 45 the elevation of the center depends only upon the outer leaves, it of course becomes evident that only the outer leaves 19 and 32 need be provided with the double row of holes. The arrangement of the parts in the 50 use of the table in the ordinary way, without the pads 26 and 27, is shown in Fig. 7, employing three leaves.

55 A slightly different form of supporting block is shown in Fig. 9. Here, a block 39 is provided with a longitudinal slot 40 and through which said block is attached to the leaves by screws 41 and 42 so as to be slidable under and from in under the runner 43, as

shown in full and dotted lines, respectively, in Fig. 9. Although only a single block has been shown in the drawings as supporting each end of the leaf upon the runner, yet two or more may be used where the width of the leaf is great enough to require such a number.

60 5 To remove most of the weight off from the dowel pins each leaf is provided with a pair of blocks 28 and 29 screwed to the respective leaves at 30 and 31 in such a manner that said blocks may be swung under the runners 13 and 14, or to the side as shown in dotted lines in Fig. 1, to correspond to the position of the leaves relative to said runners.

65 10 The elevation of the leaves may be made in two or more heights to accommodate different thicknesses of pads by employing two or more blocks 44 and 45 of different heights, as shown in Fig. 10, either of which may be swung under the runner 46. This will, however, necessitate three rows of holes instead of two in the corresponding places indicated in the previous construction.

70 15 I claim:

1. In combination with the end sections of an extension table and protective pads for covering the same, a set of leaves for said table, and means for holding said leaves assembled in the table with the surfaces thereof in a plane above that of the surfaces of the end sections and in the plane of the surfaces of said protective pads.

75 2. An extension table comprising end sections having their surfaces in fixed planes and leaves adapted to be applied in said end sections with the surfaces thereof in the plane of the surfaces of the end sections, and means for securing said leaves in the table with the surfaces thereof above the plane of the surfaces of the end sections.

80 3. A table top comprising end sections and leaves for extending the table, and means for assembling said leaves in the table so that the surfaces thereof shall be exposed and in a plane above that of the surfaces of the end sections when the table is in the extended position.

85 4. A table top comprising end sections having a set of dowel pins in said end sections, a table leaf having thickened portions provided with two sets of apertures at different levels adjacent said dowel pins in the end sections, and movable supports on said table leaf whereby the same may be assembled in the table at either of two levels to bring the surface of the leaf in the plane of the end sections or above the same, as desired.

90 5. In testimony whereof I affix my signature in presence of two witnesses.

JOHN L. MCKAY.
